UNITED STATES PATENT OFFICE.

GEORGE B. CROUSE, OF STAMFORD, CONNECTICUT.

ACOUSTIC-TRANSLATING DEVICE.

Application filed December 6, 1922. Serial No. 605,153.

The subject-matter of the present application relates to devices for translating electrical undulations into sound vibrations and the features of invention hereinafter disclosed are directed toward the improvement of such apparatus whereby sound vibrations may be faithfully reproduced.

While certain or all of the features of invention may be embodied in other forms of devices, within the scope of the appended claims, they may perhaps best be explained as embodied in a telephone receiver. In employing the term telephone receiver I mean to refer to and include not only receivers employed in land-line telephony but those employed in radio telephony and telegraphy as well.

In the receiver now commonly in use in land-line telephony, the motions of the diaphragm do not exactly correspond to the changes in current in the coils and therefore voices heard over land-line telephones do not sound quite natural. In land-line telephony the faithfulness or naturalness of the voice reproductions is of minor importance so long as the speech is intelligible. With the advent of radio telephony and use of telephone receivers as a part thereof new requirements were introduced but chiefly as to increased sensitivity. In radio telegraphy it is unnecessary that the quality or pitch of the received signals bear any exactly definite relationship to the undulations or transmitted impulses. However, in radio telephony the now common practice of broadcasting or transmitting music and speeches has introduced new and more severe requirements. It is of great importance that the music or speech at the transmitting station be faithfully reproduced as to quality as well as pitch at the receiver or receivers. The metallic diaphragms heretofore commonly employed in receivers for telephone or radio telegraph signals are open to serious objections when employed in the reception of music or speech where faithful reproduction as to quality and pitch are important. Such a metallic diaphragm has a definite natural period of vibration. It vibrates much more easily at this pitch than at any other. When a receiver embodying such a metallic diaphragm

is called upon to respond to undulations representing a musical sound consisting of a fundamental and certain definite overtones or harmonies, any harmonic of the same period as the natural period of the diaphragm will be emitted with comparative loudness while the components of other periods will be relatively suppressed. Thus the quality of the reproduced sound is quite different from the transmitted sound. Furthermore, when the transmitted sound does not comprise a fundamental or harmonic of the same period as the natural period of such a metallic diaphragm, the latter nevertheless sounds a tone of its natural period thereby changing the quality of the transmitted sound and quite often changing a transmitted musical tone or tone-combination into noise.

Among other objects the present invention has for one of its most important purposes to reduce and practically eliminate distortion of the transmitted sound in telephone receivers by providing a diaphragm which does not vibrate freely by itself and has no natural period which can be definitely distinguished. To this end, I propose to construct the diaphragm of such material, or combinations of materials, that there is a comparatively high degree of friction between its molecules. In other words, I propose to provide a diaphragm which has high internal damping. With this preliminary explanation, I now refer to the drawings, wherein I have illustrated certain now preferred physical embodiments of the invention and in which:

Fig. 1 is a plan view, with various parts broken away, illustrating a preferred form of receiver embodying certain features of the invention.

Fig. 1^a is a fragmentary sectional elevation of an instrument similar to that shown in Figs. 1 to 3 but illustrating a modification.

Fig. 2 is a sectional elevation taken substantially on the line 2-2 of Fig. 1.

Fig. 3 is a sectional elevation taken substantially on the line 3-3 of Fig. 1.

Fig. 4 is an elevation showing a modified form of the invention.

Fig. 5 is a plan view (with the dia-

phragm, cap and armature removed) of a modified form of device.

Fig. 6 is a section taken substantially on the line 6-6 of Fig. 5.

5 Figs. 7 and 8 are respectively a plan view and elevation, on a larger scale, of the diaphragm and armatures shown in Fig. 6.

Fig. 9 is a view similar to Fig. 6 but illustrating a further modification.

10 Fig. 10 is a fragmentary sectional elevation of a further modification; and,

Fig. 11 is a plan view of certain of the elements shown in Fig. 10.

15 Calling attention to Figs. 1 to 3, it will be seen that I have there illustrated a watch-case receiver comprising a cup-shaped housing or casing 10 externally screw-threaded to co-operate with the internally-threaded ear cap 11 having the central opening 12. A 20 diaphragm 13 extends across the housing 10 and is adapted to be vibrated by the preferred form of electromagnetic means which I shall now describe.

The diaphragm 13 has secured thereto, by 25 suitable adhesive material, riveting or other securing means, a disc or button 14 of soft iron or other suitable magnetizable material. The receiver is provided with the permanent magnet 15, electromagnets 17 having cores 30 or pole-pieces 16, all of which may be secured to the casing 10 in the usual way and which may be substantially of the usual construction except that the pole tips; i. e., the upper ends of the poles 16, are preferably bent toward each other as indicated in Figs. 1 and 3. The receiver may also be provided with the terminal block 18 and cord-attaching eye-member 19 of common and well-known construction.

40 The diaphragm 13 is preferably constructed of such material, or combination of materials, as to provide a diaphragm having a comparatively high degree of friction between its molecules; i. e., a comparatively 45 high degree of internal damping and having no natural period that can readily be distinguished. For example, a diaphragm built of laminations of paper, cloth, or other fibrous material, impregnated with natural or 50 synthetic gum, or other suitable binder, and baked, if desired, may be employed. At present I prefer to construct the diaphragm 13 of material known in the electrical arts as "bakelite-dilecto."

55 The efficiency of operation of receivers such as I have described, and in fact other receivers of the same general type, depends on the mean air-gap distance between the poles and armature 14. In the practical 60 construction of diaphragms such as I have above described it has been found extremely difficult to produce diaphragms which are absolutely standard as to shape; i. e., some are found to be dished more or less. Therefore, in order to manufacture such receivers

at a cost within the means of the average user, it is extremely important, if not essential, that there be some form of means for adjusting the mean distance between the armature and poles and further, it is important that this means be fairly simple. One form of such adjusting means is illustrated in Figs. 1 to 3 and may be constructed substantially as follows.

A ring or annulus 20 of spring metal, or 75 other resilient material, split at 21 is mounted at the upper end of the casing 10, the upper inner edge of the casing being bevelled and the outer lower edge of the annulus 20 being bevelled as clearly indicated 80 in Figs. 2 and 3. The diaphragm 13 is adapted to seat upon the upper face of the ring 20 and to be engaged by the annular rib 22 of the cap 11. By virtue of this construction, when the cap 11 is screwed toward 85 the casing the diaphragm 13 and ring 20 are moved toward the pole-pieces 16, such movement being opposed by the inherent resiliency of the ring 20. When the cap 11 is screwed in the reverse direction, the ring 20 90 expands, and moves outwardly forcing the diaphragm 13 against the seat 22.

Means for holding the cap 11 and casing 10 in various relative positions of adjustment are provided. A preferred form of 95 such means will be found illustrated in Figs. 1 and 2 and may be constructed substantially as follows. A strip 30 of bridge-like shape is adapted to bear at its lower end against the inner wall of the housing 10. The upper 100 end of the bridge 30 projects through an opening 31 in the housing and is adapted to engage the inner threaded wall of the cap 11. A screw 32, which passes through an opening 33 in the housing 10, screw-threadedly 105 engages a suitably tapped opening in the bridge or locking piece 30. Obviously the screw 32 may be turned in either of opposite directions and, when so moved, moves the bridge 30 into locking or release position with respect to the cap 11, depending 110 upon the direction of rotation.

The manipulation and operation of the 115 form of invention above described as applied to a radio telephone receiving apparatus may be described as follows. To adjust the air-gap the locking screw 32 is unscrewed or loosened. The ear cap 11 should then be turned in the proper direction until the armature 14 snaps against the poles 16, due 120 to magneto-motive-force of the permanent magnet 15. This may readily be detected by the click produced by such snapping of the armature into engagement with the poles. The ear cap 11 should then be turned in the 125 opposite direction until the diaphragm 13 and its armature 14 move away from the pole pieces as evidenced by a clicking sound. The exact relative position at which the diaphragm moves away from the pole pieces 130

is the least air-gap that may be employed without danger of the armature 14 sticking or freezing on the pole pieces 16 when loud sounds are received. After the air-gap adjustment has been effected the screw 32 is turned to move the bridge 30 into locking position and the telephone receiver may be connected to the receiving apparatus in the proper manner; i. e., as to polarity of the terminals. By virtue of the composition and properties of the diaphragm 13, above described, and the accuracy of adjustment of the air-gap, the sounds reproduced will be true reproductions of the sounds represented by the electrical undulations through the magnet coils.

It will be understood that two properly connected receivers each of the form illustrated in Figs. 1 to 3 would preferably be employed for a head set. For a loud speaker only one instrument would be required. Thus in Fig. 4 I have illustrated an instrument in all respects similar to that illustrated in Figs. 1, 2 and 3 except that a cap 111, of metal or other suitable material, having a sound amplifying horn 112, connected thereto, is substituted for the cap 11 of Figs. 1, 2 and 3. When a comparative large amount of current is sent through the receiver, as is the case when using the receiver for a loud speaker (Fig. 4) rattling will take place unless the diaphragm is set for a comparatively large air-gap. To avoid rattling the cap 111 may be turned in the direction to move it away from the casing 10 until the rattling disappears. An eighth of a turn should suffice for this purpose.

The invention is susceptible to modification in various respects, in addition to those above noted, without departing from the scope as defined in the appended claims. Thus, in Figs. 5 to 8 inclusive, I have illustrated a receiver with a different form of armature and pole tips and I have omitted, in these figures, the air-gap adjusting means shown in Figs. 1 to 4. The elements 210, 211, 212, 213, 215, 216, 217, and 218, shown in Figs. 5 to 8, correspond respectively to the elements 10, 11, 12, 13, 15, 16, 17, and 18, shown in Figs. 1 to 3. The armature 50 consists of a strip of soft iron bent to the form illustrated in Figs. 6 and 8; i. e., to the form of a hollow triangular prism with a joint at 51. The armature 50 may be connected to the diaphragm by screws 52 or other suitable means. It will be noted that the reluctance of the magnetic path is not appreciably increased, due to the joint or slit 51 since there is practically no cross flux across this joint. The pole tips are slightly bevelled (see Fig. 6) to conform to the shape of the armature. Due to the construction of the armature 50 and the co-operating poles 216, the former must be prevented from rotating with respect to, and

located in a definite relationship with respect to the said poles. For this purpose the casting 10 is provided with upstanding pins 55 each slightly shorter than the thickness of the diaphragm 213 and each adapted to enter a notch 55 in the diaphragm when the parts are assembled.

The operation of the instrument shown in Figs. 5 to 8 is generally similar to the instrument illustrated in Figs. 1 to 4, in that the permanent magnet passes a continuous flux through one of the poles 216, armature 50, and the other pole 216, thus exerting a continuous pull on the diaphragm 213. When an undulating current is passed through the serially, or otherwise, connected coils 217, 217, the flux across the gap is correspondingly varied to impart vibrations to the armature and diaphragm in accordance with the electrical undulations.

It should be noted that the form of pole and armature construction shown in Figs. 5 to 8 possesses the following advantages among others. For a given effective length of flux path across the gap, a greater motion of the diaphragm, before the armature contacts with the pole pieces, is available. Also, for a given reluctance of the iron armature, a relatively light armature may be employed since the flux path through the armature is short. Furthermore, since the armature extends between the pole pieces, there is very little magnetic leakage from pole tip to pole tip outside of the gap.

In Fig. 9 I have illustrated a further modification, in which two armatures are employed. The elements 310, 311, 312, 313, 315, 316, 350 correspond generally to the elements 210, 211, 212, 213, 215, 216 and 50, respectively, of Figs. 5 to 8. In Fig. 9 it will be noted that the pole pieces 316 are not bent over toward each other but are bevelled off as shown, each to co-operate with a corresponding one of the two armatures 350. The flux path between the two armatures is formed by a member 61, of iron, suitably bevelled at its opposite ends to co-operate with the armatures 350. The member 61 is supported in any suitable manner, as by means of a pedestal 60 of non-magnetic material secured to the casing and to which pedestal the member 61 is also secured.

While two armatures are employed in the form of the invention illustrated in Fig. 9, these armatures are each spaced from the center of the diaphragm so that their weight is less effective in lowering the period of the diaphragm. By placing the armatures away from the diaphragm center, the air-gap length may be decreased for a given motion of the diaphragm, and this factor offsets, to some extent at least, the effects of the increased reluctance due to the employment of the plurality of gaps in series.

In Figs. 10 and 11 I have shown a struc-

ture 71, 72, 73, 75, 76 that may be substituted for the diaphragm 213 and armature 50 shown in Fig. 6. In the forms of invention illustrated in Figs. 1 to 9 inclusive I now prefer to employ diaphragms of bakelite-dilecto. However, diaphragms of other material such as aluminum, or other metal, may be employed in at least some of the constructions illustrated in Figs. 1 to 9 with improved results over the prior art devices. In the form shown in Figs. 10 and 11 the diaphragm 71 may be constructed of aluminum, or other suitable material, in the form of a cup whose flange extends between the inner split ring 75 and an outer ring 72. The inner ring 75 may be expanded by means of a tapered screw 76, adapted to screw into the slit of the inner ring, and since the outer ring 72 is comparatively thin, the entire structure 71, 72, 75, may be expanded and the diaphragm thereby stretched. By stretching the diaphragm 71 its natural period may be raised without increasing its weight. It will be noted that the outer ring 72 is provided with an outwardly projecting ledge or flange adapted to rest upon the upper edge of the housing 210 when the elements 71, 72 (armature), 73, 75 and 76 are substituted for the armature 50 and diaphragm 213 of the device shown in Fig. 6.

Instead of employing the structure illustrated in Figs. 1 to 3 to provide for the adjustment of the mean air gap, I may employ that illustrated in Fig. 1^a. In the last mentioned figure, the diaphragm 13 is carried by the cap 11. A nut 400, externally threaded, screws into the cap 11, the diaphragm 13 being clamped between said gap and nut. The nut is provided with diametrically opposed notches 401 (one of which is illustrated in Fig. 1^a) into which a spanner wrench or other suitable tool may be inserted to screw the nut into or out of the cap 11. By virtue of this construction, the diaphragm 13 may be readily mounted in or removed from the cap 11. Obviously, by turning the cap 11 in one direction or the other with respect to the casing 10 the mean position of the armature 14 with respect to the poles of the magnets may be adjusted at will. Any desired adjustment may be held by devices 30, 31, 32, not shown in Fig. 1^a but illustrated in Figs. 1 to 3.

In addition to the advantages above set forth I wish to point out further that by virtue of the improved magnetic circuits disclosed comparatively large wire may be employed in the windings of the instruments which reduces likelihood of burn-outs, a feature which assumes particular importance when the instruments are used in connection with vacuum tube amplifiers.

In accordance with the provisions of the patent statutes, I have herein described the

principle of operation of my invention, together with the apparatus which I now consider to represent the best embodiments thereof, but I desire to have it understood that the apparatus disclosed is only illustrative and that the invention can be carried out by other means. Also, while it is designed to use the various features and elements in the combinations and relations described, some of these may be altered and others omitted and some of the features of each modification may be embodied in the others without interfering with the more general results outlined, and the invention extends to such use.

"Bakelite-dilecto" is a material made of laminations of paper impregnated with bakelite and heated and pressed. Bakelite is a product made by a chemical union of phenol and formaldehyde.

What I claim is:

1. A telephone receiver comprising in combination, a cup-shaped housing, a split annulus of resilient material mounted on the inner edge of said housing, said annulus and inner edge being provided with co-acting inclined surfaces, a diaphragm mounted on said annulus, an ear cap screw-threadedly connected to said housing and adapted to move said diaphragm toward said housing upon rotation of said cap with respect to said housing, and electro-magnetic means mounted within said housing for vibrating said diaphragm.

2. A telephone receiver as set forth in claim 1 in which means are provided for locking the cap and housing in various relative positions of adjustment.

3. A device for translating electrical undulations into sound vibrations and comprising in combination, a casing having a body portion and detachable cap portion, an electromagnet secured within said casing, a diaphragm extending across said casing, means for adjusting the position of said diaphragm by relative rotational movement of said cap portion and body portion, and means for releasably locking said cap portion and body portion in various relative positions of adjustment, said last mentioned means comprising a locking member connected to one of said portions and adapted to engage the other of said portions, and a screw for moving said locking member into engagement with said last mentioned portion.

4. A device for translating electrical undulations into sound vibrations and comprising in combination, a casing having a body portion and detachable cap portion, an electromagnet secured within said casing, a diaphragm extending across said casing, means for adjusting the position of said diaphragm by relative rotational movement of said cap portion and body portion, and

means for releasably locking said cap portion and body portion in various relative positions of adjustment, said last mentioned means comprising a bridge-shaped locking member adapted to bear at one end against said body portion and at its other end against said cap portion, and a manually

adjustable screw cooperating with said body portion and bridge-shaped locking member for moving the latter into gripping engagement with said cap portion.

In testimony whereof I hereto affix my signature.

GEORGE B. CROUSE.
